UNITED STATES PATENT OFFICE.

WILLIAM CALDWELL KEPLER, OF CONSTANTINE, MICHIGAN.

ANGLING DEVICE.

SPECIFICATION forming part of Letters Patent No. 689,497, dated December 24, 1901.

Application filed April 29, 1901. Serial No. 58,012. (No model.)

To all whom it may concern:

Be it known that I, WILLIAM CALDWELL KEPLER, a citizen of the United States, residing at Constantine, in the county of St. Joseph and State of Michigan, have invented 5 a new and useful Improvement in Angling Devices, of which the following is a specification.

My invention relates to an improvement in 10 sinkers for fishing-lines.

I attain this object by the device illustrated in the accompanying drawings.

Figure 1 illustrates a perspective view of 15 the device. Fig. 2 shows the manner of attaching the line thereto. Fig. 3 shows the line attached and ready for use.

The sinker is made of a small preferably- 20 rectangular piece of metal 1, with a rectangular slot 2 through the center and bifurcated ends 3. To place in position for use, pass a loop of the line *a* through the slot 2, spread over the bifurcated ends 3, and draw into position by a pull on the line. It will then be as illustrated in Fig. 3.

I do not wish to be understood as limiting 25 myself to a rectangular piece of metal, as a square, oval, spherical, or disk-shaped piece constructed on these specifications would be equally efficient as a sinker. It can be made by casting in molds or by die-cutting machines. 30

Having thus described my invention, what I claim as new, and wish to secure by Letters Patent, is—

1. An angling device comprising a metallic 35 body provided with a central slot and bifurcated ends, substantially as described.

2. A sinker for fishing-lines comprising a piece of metal of suitable shape, provided with a substantially rectangular slot near its 40 center and oppositely-arranged bifurcated end portions, substantially as described.

WILLIAM CALDWELL KEPLER.
